UNITED STATES PATENT OFFICE.

BERTHA SIEGENTHALER, OF ZURICH, SWITZERLAND.

GIRDLE BODICE.

Application filed October 21, 1926, Serial No. 143,227, and in Switzerland November 4, 1925.

- This invention relates to girdle-bodices which reach only to the waist of the wearer, that is, appreciably above the hips of the wearer. In the ordinary girdle-bodices, if the wearer be corpulent, her stomach will protrude over the upper edge of the bodice, thus causing an effect which is not in the least beautiful and cannot be hidden by the outer garments of the wearer.
- 10 It is the object of the present invention to provide a girdle-bodice which will hold the stomach of the wearer in its correct position and prevent any unsightly bulging over the upper edge of said bodice.
- 15 To obtain this purpose the girdle-bodice according to my invention has fastening members reaching over the waist, a bi-parted stomach bandage the halves of which adjacent to the fastening members also reach over the waist and means laterally fixed to the bodice below the waist and adapted to hold draw bands fixed to the stomach bandage which draw bands can thus be pulled in an inclined direction.
- 20 The accompanying drawing shows an example of a girdle-bodice according to this invention. Fig. 1 is a perspective view, Fig. 2 a side-elevation and Fig. 3 is a view on the inside.
- 25 In the example shown, 1 denotes the girdle-bodice which reaches only to the waist 2 of the wearer. The bodice is provided with fastening members 3 for securing it in position on the figure of the wearer, and is also provided with a bi-parted inextensible stomach bandage 4, the halves of which extend across the waist and are stitched to the bodice beneath the fastening plates 5. Each half of stomach bandage 4 is stiffened by means of stiffening strips 6 which are inserted therein, strips 6 being of any suitable shape and material.
- 30 Secured to each side of the bodice and arranged below the waist is an inextensible band 7 provided with a loop 8, which band is inclined forwardly of the wearer and upwardly. Also secured to each side of bandage 4 is a draw-band 9 having ears 10 and a hook 11. Draw-band 9 is inclined downwardly as shown in Figs. 1 and 2 and is passed through loop 8, the hook 11 being adapted to be attached to one of the ears 10 of the draw-band 9. The lower part of each bandage 4 is preferably connected to the corresponding draw-band 9 by short inextensible bands 12.
- 35 When the inclined draw-bands 9 are pulled on, the stomach is retained by the central fastening elements 3 and plates 5 and by the stomach bandage 4. The degree of the pull may vary by adjusting the draw-bands 9. No narrowing of the waist nor pressure thereupon takes place, so that the wearer is in no way incommoded by the girdle-bodice.
- 40 The bodice may also be laterally closed, instead of centrally and the stomach-bandage may consist of ordinary bodice-fabric, inextensible rubber-fabric etc.
- 45 To facilitate breathing the bodice has preferably an elastic intermediate piece in the back portion.
- 50 What I claim is:
1. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.
- 55 2. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.
- 60 3. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.
- 65 4. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.
- 70 5. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.
- 75 6. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.
- 80 7. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.
- 85 8. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.
- 90 9. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.
- 95 10. A girdle-bodice comprising fastening plates provided with fastening members for securing the girdle-bodice in position and extending appreciably above the hips of the wearer, a bi-parted stomach retaining bandage, the halves of which are secured to the girdle-bodice at the fastening plates and extend equally above the hips to the waist of the wearer, an inextensible strap secured at one end to the girdle-bodice at the side of and below each half of the bandage member, a loop on the other end of each of said straps, a draw band secured to each half of said bandage member and inclined downwardly and passed through said loop and adjustable fastening means on said draw-bands for securing each draw-band in its adjusted positions so that said draw-bands may be pulled in a downwardly-inclined direction and to obtain a controllable inwardly-directed pressure of the said stomach bandage against the stomach of the wearer and to hold and retain the stomach in its proper position without exerting pressure upon the hips of the wearer.

of and below each half of the bandage member, a loop on the other end of each of said straps, a draw band secured to each half of said bandage member and inclined down-
wardly and passed through said loop, and
adjustable fastening means on said draw-
bands for securing each draw-band in its
adjusted positions so that said draw-bands
may be pulled in a downwardly inclined di-
rection and to obtain a controllable in-
wardly-directed pressure of the said stom-

ach bandage against the stomach of the
wearer and to hold and retain the stomach
in its proper position without exerting pres-
sure upon the hips of the wearer, and an ad-
ditional inextensible strap connecting the
lower part of each half of the stomach
bandage to its respective draw-band.

In testimony whereof I have affixed my
signature.

BERTHA SIEGENTHALER.
